UNITED STATES PATENT OFFICE.

JAMES AHERN, OF WASHINGTON, DISTRICT OF COLUMBIA.

MUSIC-LEAF TURNER.

SPECIFICATION forming part of Letters Patent No. 709,625, dated September 23, 1902.

Application filed February 15, 1902. Serial No. 94,312. (No model.)

To all whom it may concern:

Be it known that I, JAMES AHERN, a citizen of the United States, residing at Washington, District of Columbia, have invented certain 5 new and useful Improvements in Music-Leaf Turners; and I do hereby declare the following to be a full, clear, and exact description of the same, reference being had to the accompanying drawings, forming a part of this 10 specification, and to the letters of reference marked thereon.

This invention relates to devices for turning the leaves or sheets of music for an instrumental performer, whereby the hands of 15 the musician are left entirely free for the manipulation of the instrument.

The objects of the invention are to provide a suitable and convenient device which may be placed on an ordinary music-rack of any 20 character and which shall be self-contained, in that when placed in position it will be ready to perform its functions and to successively turn the pages of the music at the operator's will and without the aid of mechanical manipulation other than a puff of 25 the performer's breath when it is desired to turn each sheet.

To the above ends the invention consists in a holder for the sheets of music, a spring- 30 operated turner for each sheet to be turned, retaining mechanism for holding said turners, and a releasing device for said retaining mechanism having a vane or wing for controlling the same and supported in position 35 to be readily operated by a puff of the performer's breath and preferably in such position that the performer may operate the same without changing position before the instrument or with relation to the sheets of music 40 forming the guide for the playing of the instrument.

Referring to the accompanying drawings, Figure 1 is a front elevation of a music-holder and sheet-turner embodying the present improvements. Fig. 2 is a side elevation of the same. Fig. 3 is a top plan view of the retaining and releasing mechanism. Fig. 4 is a vertical section on the line 4-4 of Fig. 3. Figs. 5 and 6 are details of one of the clamping-fingers mounted on the ends of the turning-arms for holding the edges of the sheets to be turned. Fig. 7 is a detail perspective 45 view of the retaining and releasing mechanism removed from the housing. Fig. 8 is a top plan view of the same. Fig. 9 is a detail 55 view of one of the retaining-pawls.

Like letters of reference in the several figures indicate the same parts.

The entire operating mechanism of the sheet-turner is preferably mounted upon or 60 constitutes a part of a base which may conveniently be in the form of a board A of proper size for the music to be handled and adapted to be placed on the music-rack in just the same manner as an ordinary piece of 65 music. This board or base A is preferably provided with laterally-extending arms B B, of wire or other material, having their ends bent back to form hooks or catches B' B' for holding those sheets of music which are to 70 remain in a flat position and are not adapted to be turned.

At the top of the base or board A is a housing C, in which are journaled a series of sheet-turners or turning-arms D, said arms being 75 preferably journaled on a single spindle and each provided around said spindle with a casing d, containing a spiral spring E, attached at one end to said casing and at the opposite end to the spindle E'. These springs are put 80 under tension and operate to throw the arms from the right to the left hand side in the direction in which the sheets are to be turned, and on the outer ends of the arms devices are provided for engaging each of the successive 85 sheets in such manner that as each arm is released it will turn its sheet from the right to the left hand position, as will be readily understood. For retaining the arms in the right-hand position and with the springs under tension the cylindrical casings or disks at the 90 bases of the arms are provided with notches or shoulders G, with which retaining-pawls H are adapted to engage, and it will be understood that as many arms and retaining- 95 pawls are employed as there are sheets of music to be turned, three such arms and retaining-pawls being shown in the accompanying illustration. The retaining-pawls are preferably gravitating pawls in that they drop 100 forwardly and their engaging projections co-operate with the shoulders on the arms automatically whenever said arms are turned either singly or together from the left-hand

to the right-hand position. The retaining pawls and shoulders or projections are arranged in successive order, and the upper ends of said pawls are provided with operating projections I, extending forwardly different distances, whereby they may be released successively by a suitable releasing device adapted to engage them in succession by a direct movement from front to rear. With such an arrangement if a suitable operating device or pusher K be moved against the forwardly-projecting ends of the pawls said pawls will be successively thrown out of engagement with the respective arms, and said arms under the influence of their springs will swing around from the right to the left hand position and carry with them the sheets of music with which they are in engagement. To insure the successive operation of the arms—one at each impulse of the releasing device—said arms, except the last one, are each provided with a stop projection K', arranged in proximity to the pawls and adapted to arrest the forward movement of the releasing device. Said stop projections swing with said arms and are arranged to project forwardly different distances corresponding to the positions of the operating projections on the pawls, whereby when each pawl is released the stop projection on the arm retained by that pawl will arrest the movement of the releasing device or pusher and then be moved out of position of engagement. Thus upon the next impulse of the pusher the next pawl may be operated and the movement of the pusher arrested by the next stop projection, which latter is in turn moved out of its operative position by the swinging movement of its arm, leaving the succeeding pawl in position to be operated by the next impulse of the pusher.

Obviously the releasing device or pusher might be operated in various ways; but as a most convenient and efficient way of performing this operation and without requiring a manipulation by the performer's hands and without requiring complicated and inconvenient connections whereby the operation may be carried out by an impulse of the performer's foot I now provide a wing or vane, which will operate said releasing device when impinged upon by a puff of air—as, for instance, a puff of the performer's breath—and I suspend or support said wing or vane in front of the music-sheet turner and in convenient position for the performer to blow upon said wing or vane without removing his eyes from the music or changing his position with relation to the music on the support or sheet-turner. The controlling device shown consists simply of a light rod M, suitably guided on the casing C and having at the inner end the pusher K, while at its outer end it carries or is connected with the wing or vane N. The latter preferably has its forward face concaved, so as to afford a maximum resistance to the moving current of air set up by

the puff of the performer's breath. As shown, this wing or vane N is pivotally suspended from a forwardly-extending arm O, mounted 70 on the casing, and is also pivotally connected with the rod carrying the pusher, thereby providing for the utmost flexibility of the device and insuring a successful operation with a very slight impulse applied to the wing or 75 vanes.

On the ends of each of the turning-arms there is mounted a pendulous clamp consisting of a pair of fingers, one of which, P, is preferably rigid, but pivotally connected with 80 the end of the arm, and the other of which, P', is a spring fastened at its base to the rigid member P. The lower end of the spring member P' is formed with a finger-piece P'', whereby it may be sprung away from the 85 rigid member for the admission of the edge of the sheet of music, which will be clamped thereby against the rigid member and held by the latter in proper relation to the turning-arm. The pivotal connection p between 90 said spring-clamp and arm allows for any variation in the arc described by the sheet and that described by the arm itself. With this arrangement the accurate positioning of the sheets of music with the hinged or pivotal edge of the music in alignment with the axis of the arm is unnecessary; but said sheets will be turned with the arms and properly positioned in their turned position even though the axis of the arms and of the 95 sheet be out of alignment. As a consequence the music may be placed in the turner in a more or less haphazard manner, and at the same time it will be successfully and properly turned to present the new face to the performer, permitting the playing of the instrument to be continuous and avoiding all necessity of the performer's removing his hands from the instrument to correctly position the sheets. 110

With a device such as described it is found in practice that not only are the performer's hands left entirely free for the manipulation of the instrument, but there being a direct connection between the releasing mechanism 115 and the operating wing or vane the performer is enabled to observe the music down to the last note on one page and to turn the same instantly for observation of the succeeding note on the next page without causing a break in 120 the performance.

Having thus described my invention, what I claim as new, and desire to secure by Letters Patent, is—

1. In a music-leaf turner, the combination 125 with a spring-pressed arm for turning the sheet and a detent for holding said arm in its set position with the spring under tension, of a releasing device for said detent embodying a wing or vane freely suspended in position 130 and adapted to be operated by a puff of the performer's breath; substantially as described.

2. In a music-leaf turner, the combination with a spring-pressed arm for turning the

sheet and a detent for holding said arm in its set position with the spring under tension, of a pusher for releasing said detent and a wing or vane connected with said pusher with 5 means for supporting said wing or vane in front of the arm and in position to be operated by a puff of the performer's breath; substantially as described.

3. In a music-leaf turner, the combination 10 with a spring-pressed arm and a detent for holding said arm in its set position with the spring under tension, of a releasing-pusher for said detent, a wing or vane connected therewith and adapted to be operated by a puff of 15 the performer's breath and a support for said wing or vane extending over the path of travel of the spring-pressed arm in turning a leaf; substantially as described.

4. In a music-leaf turner, the combination 20 with a spring-pressed arm and a detent for holding said arm in its set position with the spring under tension, of a pusher for releasing said detent and a freely-suspended wing or vane having a concave face, connected with 25 said pusher and supported in position and adapted to be operated by a puff of the performer's breath; substantially as described.

5. In a music-leaf turner, the combination 30 with a support, a spring-pressed arm mounted thereon and a detent for holding said arm in its set position with its spring under tension, of a longitudinally-movable rod carried by said support and extending out over the path 35 of travel of the arm, a detent-releasing device connected with the inner end of the rod and a wing or vane connected with the outer end of the rod and adapted to be moved by a puff

of the performer's breath to release the detent and allow the arm to swing; substantially as described.

6. In a music-leaf turner, the combination 40 with a plurality of independent spring-pressed arms, detents for holding said arms in set position with the springs under tension, and a pusher for releasing said detents, of pusher- 45 stops moved by the arms and adapted to arrest said pusher when an arm is released and to be moved out of the path of said pusher by the movement of the released arm; substantially as described.

7. In a music-leaf turner the combination 50 with a series of spring-pressed arms having detent-shoulders, a series of detents coöperating with said shoulders to hold the arms in set position with the springs under tension and 55 a pusher coöperating with said detents successively of independent detent-stops moving with the arms each coöperating with the pusher to arrest its movement when an arm is released and itself moved out of the path 60 of the pusher by the released arm; substantially as described.

8. In a music-leaf turner, the combination 65 with a pivoted spring-pressed arm, a detent therefor and a releasing mechanism for said detent, of leaf-clamping fingers pivotally mounted on the end of said arm whereby a leaf may be turned by said arm when the axis of the leaf and arm are out of alinement; substantially as described.
